(57) **CLAIM**

The ornamental design for a medication delivery device as shown and described.

DESCRIPTION

FIG. 1 is a front-top-right perspective view of a medication delivery device consisting of both a top and bottom portion in accordance with our design;

FIG. 2 is a rear-bottom-left perspective view of the medication delivery device of FIG. 1;

FIG. 3 is a top plan view of the medication delivery device of FIG. 1;

FIG. 4 is a bottom plan view of the medication delivery device of FIG. 1;

FIG. 5 is a left side elevational view of the medication delivery device of FIG. 1;

FIG. 6 is a right side elevational view of the medication delivery device of FIG. 1;

FIG. 7 is a front elevational view of the medication delivery device of FIG. 1;

FIG. 8 is a rear elevational view of the medication delivery device of FIG. 1;

FIG. 9 is a front-top-right perspective view of a medication delivery device consisting of the top portion of FIG. 1 in accordance with our design;

FIG. 10 is a rear-bottom-left perspective view of the medication delivery device of FIG. 9;

FIG. 11 is a top plan view of the medication delivery device of FIG. 9;

FIG. 12 is a bottom plan view of the medication delivery device of FIG. 9;

FIG. 13 is a left side elevational view of the medication delivery device of FIG. 9;

FIG. 14 is a right side elevational view of the medication delivery device of FIG. 9;

FIG. 15 is a front elevational view of the medication delivery device of FIG. 9;

FIG. 16 is a rear elevational view of the medication delivery device of FIG. 9;

(Continued)

FIG. 17 is a front-top-right perspective view of a medication delivery device consisting of the bottom portion of FIG. 1 in accordance with our design;

FIG. 18 is a rear-bottom-left perspective view of the medication delivery device of FIG. 17;

FIG. 19 is a top plan view of the medication delivery device of FIG. 17;

FIG. 20 is a bottom plan view of the medication delivery device of FIG. 17;

FIG. 21 is a left side elevational view of the medication delivery device of FIG. 17;

FIG. 22 is a right side elevational view of the medication delivery device of FIG. 17;

FIG. 23 is a front elevational view of the medication delivery device of FIG. 17; and,

FIG. 24 is a rear elevational view of the medication delivery device of FIG. 17.

In FIGS. 1-24, the thin solid lines that do not contact other solid lines represent shading or contour lines rather than claimed ornamental features. Applicant reserves the right to remove or modify these lines to clarify that the lines represent shading or contour lines.
